DESCRIPTION

FIG. 1 is a reduced side elevational view of our new flower pot cover design;

FIG. 2 is a reduced transverse sectional view thereof;

FIG. 3 is a reduced bottom plan view thereof;

FIG. 4 is a reduced top plan view thereof;

FIG. 5 is a reduced top plan view of a second embodiment of the design of FIG. 1, the only difference being the shape of the opening;

FIG. 6 is a reduced top plan view of a third embodiment of the design of FIG. 1, the only difference being the shape of the opening;

FIG. 7 is a reduced top plan view of a fourth embodiment of the design of FIG. 1, the only difference being the shape of the opening;

FIG. 8 is a reduced side elevational view of a fifth embodiment of the design of FIG. 1, the only difference being the height;

FIG. 9 is a reduced side elevational view of a sixth embodiment of the design of FIG. 1, the only difference being the height;

FIG. 10 is a reduced side elevational view of a seventh embodiment of our new flower pot cover design;

FIG. 11 is a reduced transverse sectional view thereof;

FIG. 12 is a reduced bottom plan view thereof;

FIG. 13 is a reduced top plan view thereof;
FIG. 14 is a reduced top plan view of an eighth embodiment
of the flower pot cover design, the only difference over FIG.
10 being in the shape of the opening;
FIG. 15 is a reduced top plan view of a ninth embodiment
of the flower pot cover design, the only difference over FIG.
10 being in the shape of the opening;
FIG. 16 is a reduced top plan view of a tenth embodiment
of the flower pot cover design, the only difference over FIG.
10 being in the shape of the opening;
FIG. 17 is a reduced side elevational view of an eleventh
embodiment of the flower pot cover design, the only differ-
ence over FIG. 10 being in the height; and,

FIG. 18 is a reduced side elevational view of a twelfth
embodiment of the flower pot cover design, the only differ-
ence over FIG. 10 being in the height.

The characteristic feature of the design resides in the specific
pleating arrangement, comprised of the parallel disposition
of the exterior folds in combination with the interior
V-shaped folds.

The flower pot cover has no substantial thickness.
